POURING SPOUT FOR SPRINKLER CANS

James S. McGlaughlin, 8735 Lyndon Ave., Detroit, Mich.

Filed Dec. 21, 1961, Ser. No. 68,010

Term of patent 14 years

(Cl. D58—17)

FIG. 2

FIG. 1

FIG. 1 is a front elevational view of a pouring spout for sprinkler cans embodying my new design; and FIG. 2 is a side elevational view thereof, the opposite side being a mirror image of the side shown.

The broken line representation of a sprinkler can in FIG. 1 and the fragmentary representation in FIG. 2 are for purposes of illustration only.

I claim:

The ornamental design for a pouring spout for sprinkler cans, as shown and described.
